V. STANLEY

SYSTEM FOR TRAIN CONTROL

Filed Oct. 29, 1923.

INVENTOR.

V. Stanley

BY
Watson E. Coleman
ATTORNEY.

UNITED STATES PATENT OFFICE.

VONGO STANLEY, OF BURLINGTON, IOWA, ASSIGNOR OF ONE-HALF TO JOSEPH MILLER,
OF BURLINGTON, IOWA.

SYSTEM FOR TRAIN CONTROL.

Application filed October 29, 1923. Serial No. 671,539.

To all whom it may concern:

Be it known that I, VONGO STANLEY, a citizen of the United States, residing at Burlington, in the county of Des Moines and 5 State of Iowa, have invented certain new and useful Improvements in Systems for Train Control, of which the following is a specification, reference being had to the accompanying drawings.

10 This invention relates to a system for train control and it is an object of the invention to provide a novel and improved system of this general character wherein the signals are arranged within the cab of the 15 locomotive and under control of a block signal or the like wherein the engineman can readily determine the condition relative to the block ahead.

It is also an object of the invention to 20 provide a system of this general character provided with novel and improved means whereby the train will automatically be brought to a stop in the event the train passes beyond a danger signal.

25 An additional object of the invention is to provide a novel and improved system of this general character whereby the train will be automatically caused to come to a stop in the event the rail of a trackway is 30 broken as by an open switch.

The invention consists in the details of construction and in the combination and arrangement of the several parts of my improved system for train control whereby 35 certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:—

45 Figure 1 is a diagrammatic view illustrating the train carried portion of the system as comprised in the invention as herein disclosed;

50 Figure 2 is an enlarged fragmentary detailed view partly in section and partly in elevation of one of the circuit closers as herein embodied;

Figure 3 is a diagrammatic view illustrat-

ing the features of the system associated 55 with the trackway;

Figure 4 is an enlarged fragmentary view partly in section and partly in elevation illustrating in detail the contact means 60 associated with the semaphore;

Figure 5 is an enlarged fragmentary view partly in section and partly in top plan of the circuit closing means under control of a switch tongue or the like.

As disclosed in the accompanying drawings, T denotes a trackway divided as at 1 into blocks and in close proximity to the meeting ends of adjacent blocks is a semaphore 2 operating in a well known manner. The semaphore 2 as herein disclosed, carries 70 a yieldable contact member 3 herein disclosed as grounded through the instrumentality of the conductor a.

The supporting standard 4 for the semaphore 2 as herein disclosed, is provided with 75 an arcuate plate 5 positioned adjacent to the semaphore 2 and provided with the spaced contacts x, y and z. At a predetermined point in advance of the semaphore 2 the trackway T is provided between the rails thereof with the spaced contact members x', y' and z', the contact member x' being 80 in electrical connection with the contact x through the medium of a conductor b, the contact y' being in electrical connection 85 with the contact y through the instrumentality of the conductor c and the contact z' being in electrical connection with the contact z through the conductor d.

The contacts x', y' and z' are transversely 90 spaced with respect to the trackway and are adapted to be engaged by the brushes x'', y'' and z'', respectively, carried by the locomotive.

Suitably positioned within the cab of the 95 locomotive are the signals 6, 7 and 8, each of said signals being herein disclosed as an electric lamp, the signal 6 being white, the signal 7 being red and the signal 8 being green, said lamps when burning serving to 100 indicate to the engineman the condition of the block ahead.

Carried by the engine is a conductor e leading from a suitable source of E. M. F. and with which is associated a second conductor f suitably grounded as indicated at 105 9.

Each of the signals 6, 7 and 8 is comprised in a lamp circuit 10 connecting in

parallel with the main circuit as afforded by the conductors *e* and *f* and each of the circuits 10 is normally open. Each circuit 10 is normally maintained open by a 5 sliding member 11 of fibre or other suitable insulating material supported for requisite movement by a guide bracket 12. The member 11 has disposed therethrough a plug 14 of conductive material and with 10 which is adapted to engage the spring contacts 15 at opposite sides of the member 11 and interposed in the line 10. Normally, the member 11 is in a position whereby the plug 14 is free of the contact members 15 and thus breaking the lamp circuit but upon movement of the member 11 in one direction, the plug 14 is brought into a position, Figure 2, to permit said contacts 15 to engage the plug 14 whereby the lamp 15 circuit is closed. One end portion of the member 11 is provided with a metallic head 16 which, upon energizing of the adjacent magnet 17, is caused to move the member 11 to effect the desired closing of a lamp 20 circuit and upon manually breaking said lamp circuit as through the medium of the switch 18, the resultant de-energizing of the magnet 17 will result in dropping of the member 11 whereby the plug 14 is moved 25 into a position free of the contacts 15. After a lamp circuit has been broken by opening the switch 18, said switch is then closed. The circuit for each of the magnets 17 comprises a leg *g* in electrical connection with the conductor *e* and a leg *h* in electrical connection with the line 10.

When the semaphore is in its lowered position or in a position to indicate the following block to be clear, the contact member 3 carried by the semaphore 2 engages the contact *x* so that when the brush *x''* comes into contact with the conductor *x'* a circuit will be closed through the conductor *b* and through the branch line *i*, said branch *i* leading from the brush to the line 10. The circuit is then continued through the line 10 to the conductor *e*. The closing of the circuit results in the energizing of the magnet 17 associated with the lamp 6 whereupon the circuit 10 for the lamp 6 is closed through the plug 14 and contact members 15.

If the semaphore 2 is in a position of caution, the circuit for initially energizing the desired magnet 17 will be completed for the green light through the conductors *a*, *d* and brush *z''* and when the semaphore is in danger position the circuit for the lamp 7 will be closed through the conductors *a* and *c*.

In relatively close proximity to the semaphore 2 and positioned between the rails of the trackway *T* are the spaced contact members 19, 20 and 21, the contact 19 being in electrical connection through the line

m with the line *d*, the contact 20 being connected through the line *n* with the line *c* and the contact 21 being connected through the line *o* with the line *b*. The contact members 19, 20 and 21 are of such length 70 that when the train comes to a standstill when the semaphore is in danger position, the brushes *y'', z''* and *x''* are in contact respectively with the contact members 19, 20 and 21. By this means when the semaphore 75 2 changes its position either to caution or clear, the circuits will be properly closed so that the lamps 6 or 8 will be caused to give the requisite indication to the engineman.

I also provide means whereby the train will automatically be caused to come to stop in the event the train passes by the semaphore 2 when in danger position and as herein disclosed such arrangement comprises a branch pipe 22 in communication with the line 23 of the air brake system and which pipe 22 opens to the atmosphere but is normally closed by the valve 24. The valve 24 as herein disclosed, is of a 85 swinging type and is directly supported by the frame 25. The valve 24 is maintained in closed position with respect to the branch 22 through the instrumentality of the fuse 26 connected at one end portion 90 to the frame 25 and at the opposite end portion to an adjustable block 27, said block 27 being adapted to be adjusted in order to properly set the fuse 26 through the instrumentality of the screw 28. The fuse 26 100 is interposed in a circuit afforded by the conductor *a* and the branch *p* in electrical connection with the conductor *f*. The line *p* however is normally opened through the medium of the spaced contacts 29 but is 105 adapted to be closed by the movable contact member 30 positioned in relatively close proximity to the contacts 29.

The contact member 30 comprises a rod 110 slidably supported by a block 31, said contact member intermediate its ends having disposed therearound an annular groove 32 in which engages an end portion of a sliding arm 33 whereby the contact member 30 is normally held in open position. The arm 33 is provided with a metal head 34 or the like adjacent to the electro-magnet 35. One leg *r* of the operating circuit and the magnet 35 is in electrical connection with the conductor *a* and the second leg *s* 120 is in electrical connection with a shoe 36.

When the train passes by a danger block or beyond the semaphore 2 the shoe 36 will engage a contact member 37 in electrical connection with the conductor *c* through the medium of the conductor *t* and with the semaphore 2 in danger position a circuit 125 will be closed to energize the magnet 35 whereupon the arm 33 will be withdrawn from working engagement with the contact 130

member 30 and said member 30 will be forced by the spring 38 into proper engagement with the contacts 29 closing the circuit through the line *p*. The force of the 5 circuit through the line *p* will result in the breaking of the fuse 26 whereupon the air pressure within the brake system will unseat the valve 24 resulting in such reduction of the pressure to cause the brakes to 10 be automatically set and the train brought to a standstill.

I also disclose means whereby the train may be automatically brought to a stop in the event a rail of the trackway becomes 15 broken as by an open switch. As particularly illustrated in Figure 3 I provide at a point in advance of the switch A a contact member 39 positioned to be engaged by the shoe 36, said contact member 39 being 20 in electrical connection through the medium of the conductor *v* with a stationary contact member 40, with which engages a contact member 41 movable with the switch said member 41 being grounded through the 25 medium of the conductor *w*. When the switch A is closed the contact member 41 is free of the contact 40 but upon opening of the switch A the contacts 40 and 41 come into engagement whereby the contact member 39 is grounded so that when 30 the brush 36 comes in contact therewith the magnet 35 will be energized to release the arm 33 from the contact 30.

I also find it of advantage to provide 35 means whereby the light 7 may be caused to burn in the event the train is broken or separated as by an open switch, and as herein disclosed the contact member *y'* is in electrical connection through the medium 40 of the contact member *w'* with a second stationary contact 42 with which the contact member also engages when the switch is open to effect the desired grounding of the circuit as the brush *y''* comes 45 into engagement with the contact *y'* to initially energize the magnet 17 associated with the light 7.

From the foregoing description it is thought to be obvious that a system for 50 train control constructed in accordance with my invention is particularly well adapted for use by reason of the convenience and facility with which it may be assembled and operated, and it will also be obvious that 55 my invention is susceptible of some change and modification without departing from the principles and spirit thereof and for this reason I do not wish to be understood as limiting myself to the precise arrangement and formation of the several parts 60 herein shown in carrying out my invention in practice except as hereinafter claimed.

I claim:-

1. A railway control apparatus comprising, in combination with a trackway, a con- 65

tact positioned adjacent the trackway, a ground line leading from the contact, a circuit closer interposed in said line comprising a stationary contact and a movable contact, said movable contact constituting the 70 semaphore of a track signal, a main circuit carried by the train, a lamp circuit connected in parallel with the main circuit, a normally open switch interposed in the lamp circuit, an electro-magnet for moving 75 the last named switch into closed position, the last named switch into closed position, and a shoe carried by the train for engagement with the track contact, a leg of the operating circuit for the electro-magnet being 80 connected with the line of the main circuit and with the line of the lamp circuit, said line of the lamp circuit being also connected to the shoe.

2. A railway control apparatus comprising, in combination with a trackway, a contact positioned adjacent the trackway, a ground line leading from the contact, a circuit closer interposed in said line comprising a stationary contact and a movable contact, said movable contact constituting the 90 semaphore of a track signal, a main circuit carried by the train, a lamp circuit connected in parallel with the main circuit, a normally open switch interposed in the lamp circuit, an electro-magnet for moving 95 the last named switch into closed position, a shoe carried by the train for engagement with the track contact, a leg of the operating circuit for the electro-magnet being connected with the line of the main circuit 100 and with the line of the lamp circuit, said line of the lamp circuit being also connected to the shoe, and a switch operating independently of the first named switch interposed in the lamp circuit. 105

3. A railway control apparatus comprising, in combination with a trackway, a contact positioned adjacent the trackway, a ground line leading from the contact, a circuit closer interposed in said line comprising a stationary contact and a movable contact, said movable contact constituting the 110 semaphore of a track signal, a main circuit carried by the train, a lamp circuit connected in parallel with the main circuit, a normally open switch interposed in the lamp circuit, an electro-magnet for moving the last named switch into closed position, a shoe carried by the train for engagement 115 with the track contact, a leg of the operating circuit for the electro-magnet being connected with the line of the main circuit and with the line of the lamp circuit, said line of the lamp circuit being also connected to the shoe, and means operating to ground the 120 track contact upon breaking of a rail of the trackway. 125

4. In combination with the air line of a pneumatic brake of a train having a branch 130 for communication with the atmosphere, a

train control comprising a valve for normally closing the branch against communication with the atmosphere, a fuse for holding the valve in closed position, a normally open circuit in which the fuse is interposed, automatically operated means for closing said circuit, and adjustable means coacting with the fuse for setting the same.

5. In combination with the air line of a pneumatic brake of a train having a branch for communication with the atmosphere, a train control comprising a valve for normally closing the branch against communication with the atmosphere, a fuse having one end portion secured to the valve, an adjustable block to which the opposite end portion of the fuse is connected to hold the valve in closed position, a normally open circuit in which the fuse is interposed, and means for closing said circuit.

6. In combination with the air line of a pneumatic brake of a train having a branch for communication with the atmosphere, a train control comprising a valve for normally closing the branch against communication with the atmosphere, a fuse for holding the valve in closed position, adjustable

means coacting with the fuse for setting the same, a normally open circuit in which the fuse is interposed, a movable contact member for closing said circuit, means for maintaining said movable contact in open position, and coacting means carried by the train and the trackway for releasing the holding means for the movable contact.

7. In combination with the air line of a pneumatic brake of a train having a branch for communication with the atmosphere, a train control comprising a valve for normally closing the branch against communication with the atmosphere, a fuse for holding the valve in closed position, adjustable means coacting with the fuse for setting the same, a normally open circuit in which the fuse is interposed, a movable contact member for closing said circuit, means for maintaining said movable contact in open position, a semaphore, and means coacting with the semaphore when in one position to render inoperative said last named means.

In testimony whereof I hereunto affix my signature.

VONGO STANLEY.
